UNITED STATES PATENT OFFICE

FRANK H. KNEELAND, OF CHICAGO, ILLINOIS, ASSIGNOR TO SAFETY MINING COMPANY, OF CHICAGO, ILLINOIS, A CORPORATION

BLASTING CARTRIDGE

Application filed October 26, 1929. Serial No. 402,619.

The present invention relates to blasting cartridges of the type comprising a metallic casing having a gas chamber formed therein for the reception of a compressed gas charge and an electrically energizable heater unit 5 therein for causing expansion of the charge. More particularly, the invention is concerned with an improved and greatly simplified method and means whereby the heater unit may be connected with a source of electricity.

The principal object of the invention is to simplify blasting cartridges of the type referred to.

Another object of the invention is to provide an improved means of including a heater unit in circuit with a source of electricity.

Other objects reside in features of construction and relationship of parts as exemplified 20 in the accompanying drawings.

Referring to the drawings,

Figure 1 is a view in longitudinal section of a cartridge embodying my invention,

Figure 2 is a transverse section on line 2-2 25 of Figure 1.

Figure 3 is a detail view of the insulating members of Figure 1.

Figure 4 is a view in longitudinal section illustrating a modified form of my invention,

Figure 5 is a transverse section on line 5-5 30 of Figure 4, and

Figure 6 is a detail view of the contact ring of Figure 4.

The invention is herein represented in a 35 blasting cartridge which consists of a cylindrical metallic casing 1 having an internal gas chamber 2, the open end of which is closed by a pressure responsive rupturable disc 3. A shear ring 4 is positioned adjacent the disc 3 and is secured in such position by 40 means of a discharge cap 5 which may be screw threaded or otherwise adjustably connected with the end of the cartridge. A cap 5 is provided with a plurality of discharge 45 ports 6. The cartridge thus formed is designed to be charged with a compressed gas and is provided with a suitable heat producing unit 8 by means of which the pressure of the gas is increased to such a point as to cause 50 rupture of the disc 3.

In cartridges of this type the heat producing unit 8 is usually designed to be energized by the passage of an electric current there-through and for this purpose it has heretofore been proposed to provide an electrode 55 extending through the body of the cartridge and insulated therefrom whereby to provide a circuit including the electrode, the heater, and the metallic body of the cartridge. The present invention is concerned with an improvement in the method and means of providing a circuit for an electrically energizable heater unit. According to the present invention, this is accomplished by insulating the discharge assembly from the body of the 60 cartridge and arranging the heater in such a way that its terminals contact with an element of the discharge assembly and with the cartridge body respectively. Thus, the rupturable disc 3 and shear ring 4 may be regarded as the discharge assembly and in the 65 form of the invention shown in Figure 1 these elements are completely insulated from the body of the cartridge by means of an insulating member 7, the exact form of which is 70 more clearly illustrated in detail in Figure 3. In the construction shown in Figure 1 the insulating member 7 is extended outwardly to the end of the cartridge and is formed with screw threads corresponding to the threads 75 formed internally of the cartridge body. The discharge cap 5 is adapted to engage the threads formed in the insulating member 7 and to be threaded into the cartridge to the point where its inner end is in engagement 80 with the shear ring. Thus, the discharge cap 5, as well as the discharge assembly 3 and 4, is effectively insulated from the cartridge body. With the construction described the two poles of a source of electricity may be 85 connected to the discharge cap or any portion of the discharge assembly and to the cartridge body as indicated at 11 and 12 respectively in order to provide a circuit for the heater unit 8 which has its contacts in engagement with the cartridge body and metallic disc 3 respectively.

In the modified construction shown in Figure 4, the discharge cap 5 is not insulated from the body of the cartridge, but the mem- 100

ber 7 serves to insulate the discharge assembly consisting of the disc 3 and shear ring 4 with respect to the body of the cartridge. Thus, in order to complete a circuit through the heater it is necessary that one connection be made to the discharge assembly and for this purpose a metallic ring 10 is positioned adjacent the shear ring 4. This ring 10 is suitably insulated from the discharge cap 5 by means of an insulating ring 9. Connection may be made to a lug 11 formed on the ring 10. The body of the cartridge is provided with one or more apertures 12 through which a wire may be passed to provide the other connection for the circuit.

In view of the foregoing description, it should be appreciated that the present invention obviates the necessity of using a separate electrode extending through and insulated from the body of the cartridge. By the present invention the necessary elements of the discharge assembly are made to serve the purpose of the electrode and the cartridge construction is thereby considerably simplified.

I claim:

1. A blasting cartridge comprising a metallic body having a discharge opening, a discharge assembly associated therewith and insulated from said body, and an electrically energizable heater unit having contacts engaging said body and discharge assembly respectively.

2. A blasting cartridge comprising a metallic body having a discharge opening, a rupturable metallic closure for said opening, means for insulating said closure from said body, and an electrically energizable heater having contacts engaging said body and closure respectively.

3. A blasting cartridge comprising a metallic body having a discharge opening, a metallic closure for said opening, means for insulating said closure from said body, an electrically energizable heater having contacts engaging said body and closure respectively, and means in electrical connection with said closure adapted for connection with one pole of a source of electricity and means for connecting the other pole of said source of electricity to said body.

4. A blasting cartridge comprising a metallic casing having a discharge opening, a rupturable closure for said opening, a discharge cap having adjustable connection with said casing and cooperating with said closure to maintain the same in sealed relation with said opening, and means for insulating said closure from said casing and discharge cap, whereby it is adapted to serve as an electrode for conducting electricity to the interior of said casing.

Signed at Chicago, Illinois, this 17th day of October, 1929.

FRANK H. KNEELAND.
